[57] CLAIM

The ornamental design for a laser pattern generator, as shown and described.

DESCRIPTION

The file of this Patent contains at least one photograph executed in color. Copies of this Patent with color photographs will be provided by the Patent and Trademark Office upon request and payment of the necessary fee.

FIG. 1 is a perspective view of a laser pattern generator embodying my design;

FIG. 2 is a front elevational view thereof;

FIG. 3 is a rear elevational view thereof;

FIG. 4 is a left elevational view thereof;

FIG. 5 is a right elevational view thereof;

FIG. 6 is a top view thereof; and,

FIG. 7 is a bottom view thereof.

The colors shown in the photographs for FIGS. 1 through 7 do not constitute an integral part of the claimed design.
